[57] **ABSTRACT**

A qualitative and quantitative determination of procainamide blood levels may be obtained by contacting a sample of urine or denatured blood with dimethylcinnamaldehyde in the presence of an acid and comparing the resulting characteristic color with a reference standard.

6 Claims, No Drawings

**METHOD FOR DETERMINING PROCAINAMIDE
LEVELS IN BLOOD OR URINE**

BACKGROUND OF THE INVENTION

Procainamide is employed medicinally as a cardiac depressant in ventricular and atrial arrhythmias. For such applications it is desirable and often necessary to determine blood levels of procainamide. Present methods for this determination are time consuming, expensive and require skilled personnel.

OBJECTS OF THE INVENTION

It is an object of the present invention to provide a simple, rapid, reliable and inexpensive method for determining procainamide levels in a particular patient. Another object is to provide a method wherein a cardiologist can obtain an immediate and accurate determination of a patient's procainamide levels. Another object is to provide a method which can be performed reliably by unskilled personnel. These and other objects of the present invention will be apparent from the following description.

DETAILED DESCRIPTION

It has now been found that the reaction of procainamide present in urine or denatured blood with 4-dimethylcinnamaldehyde in the presence of an acid produces a characteristic color ranging from light pink to rose depending upon the amount of procainamide present in the sample. The method of the present invention may be carried out by adding a drop of urine or denatured blood to a small quantity of 4-dimethylcinnamaldehyde and comparing the resulting color with a predetermined standard. The blood may be denatured by contacting an approximately 0.1 N solution of hydrochloric acid or an equivalent amount of another acid, or by contacting an acidic ion exchange resin. Examples of acids which may be used in addition to hydrochloric are the following: acetic, trichloroacetic, sulfamic, nitric, sulfuric or sulfosalicylic. As examples of acidic ion exchange resins there may be mentioned sulfonated styrene-divinylbenzene copolymers such as Amberlite IR-120, Amberlite IR-200, Dowex 50, Dowex 50W, Dowex MPC-1, Duolite C-20, Duolite C-25, Ionac C-240 or Ionac C-250, and resins prepared by crosslinking an unsaturated carboxylic acid such as acrylic, methacrylic or maleic with a crosslinking agent such as divinylbenzene or ethylene dimethacrylate such as Amberlite IRC-50, Amberlite IRC-84, Duolite CS-101, or Ionac C-270. The ion exchange resin and the 4-dimethylcinnamaldehyde may be employed in separate layers.

The blood may be denatured prior to contacting the 4-dimethylcinnamaldehyde or by contacting simultaneously the acid and 4-dimethylcinnamaldehyde.

The amount of 4-dimethylcinnamaldehyde employed per drop of blood or urine is in the range of from about 5 mg to about 50 mg. Greater amounts of the aldehyde may be used but are uneconomical. The quantity of acid employed per drop of blood is that quantity sufficient to denature the proteins present in the blood. Typically, the amount of acid will be from 5-10 drops of 0.1 N HCl or its equivalent, for example, 1 drop (approximating 1 minim) of 30 percent trichloroacetic acid. Antioxidants may be employed if desired to stabil-

ize the aldehyde. Examples of suitable antioxidants are BHT, vitamin E, tocopherols, and the like.

By previous experiment it has been found that differing levels of procainamide in urine or denatured blood give the following characteristic color when reacted with 4-dimethylcinnamaldehyde:

	Procainamide levels	Color
10	2 μ g	light pink
	5 μ g	pink
	7 μ g	light rose
	10 μ g	rose

The following examples illustrate the present invention without, however, limiting the same thereto.

EXAMPLE 1

Five mg of 4-dimethylcinnamaldehyde are added to a centrifuge tube. A cone shaped section of filter paper is inserted in the top of the tube and 5 drops (each approximating 1 minim) of about 1 normal HCl are placed on the filter paper followed by 1 drop of blood approximating 1 minim and containing 2 μ g of procainamide. When the clear filtrate passes through the filter paper and contacts the 4-dimethylcinnamaldehyde, a characteristic light pink color is produced.

EXAMPLE 2

30 The procedure of Example 1 is repeated except that 15 mg of 4-dimethylcinnamaldehyde are placed in the tube and 2 drops (each approximating 1 minim) of 30 percent trichloroacetic acid is substituted for hydrochloric acid. A drop of blood approximating 1 minim and containing 5 μ g of procainamide is placed on the filter paper. When the clear filtrate passes through the filter paper and contacts the 4-dimethylcinnamaldehyde, a characteristic pink color is produced.

EXAMPLE 3

35 The procedure of Example 2 is repeated except that 5 μ g of powdered sulfamic acid are substituted for the trichloroacetic acid and the drop of blood approximating 1 minim contains 7 μ g of procainamide. In this case the color produced when the clear filtrate contacts the 4-dimethylcinnamaldehyde is a light rose.

EXAMPLE 4

40 The procedure of Example 2 is repeated except that 5 drops (each approximating 1 minim) of acetic acid are substituted for the trichloroacetic acid and 5 mg of 4-dimethylcinnamaldehyde are placed in the bottom of the tube. A drop of blood approximating 1 minim and containing 10 μ g of procainamide is added to the filter paper. When the clear filtrate contacts the 4-dimethylcinnamaldehyde, a characteristic rose color is produced.

EXAMPLE 5

45 About 5 mg of 4-dimethylcinnamaldehyde are added to a test tube and then about 5 mg of a sulfonated styrene divinylbenzene copolymer (Amberlite IR-120) are added. A drop (approximating 1 minim) of blood containing 5 μ g of procainamide is added and there is produced a characteristic pink color.

EXAMPLE 6

The procedure of Example 5 is repeated except that the acidic ion exchange resin and the 4-dimethylcinnamaldehyde are thoroughly mixed before being added to the test tube. When the drop (approximating 1 minim) of blood is added, the characteristic pink color is produced.

EXAMPLE 7

Ten mg of 4-dimethylcinnamaldehyde are placed in a test tube followed by a drop (approximating 1 minim) of 0.1 N HCl and a drop of urine containing 7 μ g of procainamide. When the urine contacts the 4-dimethylcinnamaldehyde, the characteristic rose color is 15 produced.

EXAMPLE 8

The procedure of Example 5 is repeated except that a drop (approximating 1 minim) of urine containing 2 μ g of procainamide is substituted for the blood. In this

case the characteristic light pink color is obtained.

What is claimed is:

1. A method for determining procainamide blood levels which comprises contacting urine or denatured blood with 4-dimethylcinnamaldehyde in the presence of an acid and comparing the resulting color with a predetermined standard.
2. A method according to claim 1 wherein the acid is acetic, trichloroacetic, sulfamic, nitric, sulfuric or sulfosalicylic.
3. A method according to claim 1 wherein the blood is denatured by contacting an acidic medium.
4. A method according to claim 3 wherein the acidic medium is an acidic ion exchange resin.
5. A method according to claim 4 wherein the acidic ion exchange resin and the 4-dimethylcinnamaldehyde are in intimate admixture in a single layer.
6. A method according to claim 4 wherein the acidic ion exchange resin and the 4-dimethylcinnamaldehyde are in separate layers.
